GAS LAMP

Richard F. Van Tubergen and Charles A. Mueller, Santa Fe, N. Mex., assignors to Breese Industries, Inc., Santa Fe, N. Mex., a corporation of New Mexico

Application July 6, 1959, Serial No. 56,677

Term of patent 14 years

(Cl. D48—20)

Fig. 1.

Fig. 2.

Figure 1 is a side elevational view of a gas lamp showing our new design, the design of the lamp being the same as viewed from all sides; and
We claim:

The ornamental design for a gas lamp, as shown and described.
